(57) **CLAIM**

The ornamental design for a slide rail as shown and described.

DESCRIPTION

Fig. 1.1 is a perspective view of the slide rail of the present design with closed pull-out drawer slides.

Fig. 1.2 is a partial enlarged perspective view of the portion of the slide rail of Fig. 1.1 shown within the dashed line.

Fig. 1.3 is a perspective view of the slide rail of Fig. 1.1 shown with extended pull-out drawer slides.

Fig. 1.4 is a perspective view of the slide rail of Fig. 1.1 with extended pull-out drawer slides with a front portion and a rear portion of the drawer slide identified with dashed lines.

Fig. 1.5 is a partial enlarged perspective view of a front portion of the slide rail of Fig. 1.4.

Fig. 1.6 is a partial enlarged perspective view of a rear portion of the slide rail of Fig. 1.4.

The rectangles formed by dashed lines appearing in Figs. 1 and 4 are for the purpose of depicting the enlarged portions and form no part of the design. Further, the elongated oval cut-outs shown in Figs. 5 and 6 are for the purpose of depicting a cut-out for showing internal portions.
